UNITED STATES PATENT OFFICE.

JOHN M. KAISER, HERBERT L. GRAY, AND JOHN C. KAISER, OF ROCK ISLAND, ILLINOIS.

MOP.

Application filed May 28, 1920. Serial No. 384,925.

To all whom it may concern:

Be it known that we, JOHN M. KAISER, HERBERT L. GRAY, and JOHN C. KAISER, citizens of the United States, and residents of 5 Rock Island, in the county of Rock Island and State of Illinois, have invented a new and useful Improvement in Mops, of which the following is a full, clear, and exact description.

10 Our invention relates to improvements in mops, and it consists in the combinations, constructions, and arrangements herein described and claimed:

An object of our invention is to provide 15 a mop having a continuous belt of absorbent material arranged to be guided in turn into operative contact with the surface of the work to be washed, immersed in a liquid, such as water or the like, and then passed 20 through a wringing device into operative contact with the surface of the work again.

A further object of our invention is to provide a device of the type described provided with a motor for the operation thereof, 25 the motor being designed to be actuated by an electrical current obtained from an ordinary source of supply as by connection with electrical conducting means usually installed in dwelling houses, wherefor the device 30 may be used wherever an electrical current is available.

A further object of our invention is to provide a device of the type described that is relatively simple in construction, easy to 35 operate, and not likely to get out of order easily.

A further object of our invention is to provide a device of the type described that is thoroughly practical commercially.

40 Other objects and advantages will appear in the following specification, and the novel features of the invention will be particularly pointed out in the appended claim.

Our invention is illustrated in the accompanying drawings, forming part of this application, in which

Fig. 1 is a side view of the device partly broken away,

Fig. 2 is an end view of the same,

50 Fig. 3 is a detailed view of a fragmentary portion of the device,

Fig. 4 is a section along the line 4—4 of Fig. 1.

55 In carrying out my invention, I provide a supporting frame or base having a body portion 1 and side portions 2. Oppositely

disposed compartments 3 and 4 are provided adjacent to the side portions 2 of the base, as best seen in Figures 1 and 4. It will be noted that the compartments 4 are inclined 60 with respect to the compartments 3 for a purpose hereinafter described. A roller supporting means is disposed in each of the compartments 3 and 4 and consists of a bearing 5 in which is inserted one end of a shaft 65 8. The bearings are maintained in the compartments by plates 6. Rollers 7 are rigidly mounted on the shafts 8. It is to be noted that a stem 9 extends upwardly from each bearing 5, being formed integrally therewith or rigidly secured thereto, and that the upper end of the stem 9 is slideable in a boss 10 which projects laterally from the side 2. A cap plate 11, which is adjustably secured to the boss 10 by means of the set 70 75 screw 12, prevents lateral displacement of the stem 9. The set screw 12 is screwed into openings in the plate 11 and the boss 10 and is rigidly carried by the latter. Bearings 5 are normally pressed downwardly by 80 means of springs 13, but may be forced upwardly when the surfaces of the rollers 7, which normally extend below the bottom of the side portions 2, encounter inequalities in the surface being traversed. 85

A pair of wheels 14 are mounted upon shafts 15. The latter are journaled in the sides 2 adjacent one end thereof. A third wheel 16 is mounted upon a shaft which has its ends journaled in the forks 17 of an upright rod 18. The latter is pivoted in a bracket 19, which is secured to the other end of the base 1 by means of bolts 20, the rod 18 being maintained in position by means of a nut or washer 21 which is carried at the 95 upper end thereof.

We mount a tank 22 upon the base 1, securing the same thereon by means of fastening plates 23, which are secured to the base by bolts 24. Surmounting the tank 22 and resting on the cover therefor is a base or support 25 for a motor 26. The latter is elevated from the base 25 by a subbase 36 which is bolted to the base 25 by means of bolts 37, the motor 26 being secured thereto by means of bolts 43. 100

The drive shaft 27 of the motor 26 projects slightly beyond one side of the tank and has a gear 29 rigidly secured thereto. The gear 29 is in mesh with an intermediate 105 gear 30 which is mounted for rotation on a stub shaft 31. The latter is secured in a

vertical support 32 which is formed integrally with the base 25 or may be formed separately and secured thereto. The intermediate gear 30 is in mesh with a third gear 34 which is carried at the end of a shaft 35. The shaft 35 has its ends journalled in the side portions 39 of the motor base 25. A roller 36' is mounted upon the shaft 35 for rotation therewith and is consequently driven by the motor 26. A gear case 28 encases the gears 29, 30, and 34, as shown, being removably secured in place in any suitable manner. The gears 29, 30, and 34 are stepped in size, as shown, and are preferably rawhide gears, since it is desirable that durable, elastic, and noiseless gears be provided. It will, of course, be understood that the base 25 is formed suitably to permit operation of the roller 36' and also the operation of a roller 38, which is positioned at a spaced distance from the roller 36', being mounted for rotation with a shaft 40 which has its ends journalled in bearings 41 (see Fig. 3). The bearings 41 are slidably disposed in key-ways 42 which are provided in the side portions 39 of the base 25. The position of the bearings 41 may be varied by means of keys 44 which are screwed in each end of the side portions 39, as clearly shown in Fig. 3.

Additional guide rollers 45 are positioned for free rotation within the tank 22. A continuous belt 46 which has a width slightly less than that of the tank 22, is passed around the various rollers, as best seen in Fig. 1. The belt 46 is formed of any suitable, durable, absorbent material and is the immediate means employed in accomplishing the functions ordinarily accomplished with a mop.

From the foregoing description of the various parts of the device, the operation thereof may be readily understood. The tank 22 is kept partly filled with water. It is obvious that when the device is moved over a surface, the operation of the rollers 7 and 45 will cause the belt 46 to contact with the surface of the floor or the like, to then be passed through the water in the tank 22, then fed between the rollers 36' and 38 which are operated in the same manner as the rollers in a wringer. The moistened belt 46 then contacts with the floor or the like again, effectually cleansing the surface thereof. The roller 45 and the roller 7, carried by the inclined recess 4, also act as automatic tightening means for the belt 36. An outlet 47 is provided to permit emptying of the tank 22 when the contents thereof has become filled with sediment wrung from the belt 46 by action of the rollers 36' and 38. A

handle 48 is secured to the device, as shown, to provide a convenient means for operating the same.

Electrical conducting wires 49 are arranged to enter the handle 48, a plug 50 being carried at the end thereof for breaking or establishing a circuit, as desired. The plug 50 is insertable in a socket 51. Electrical conducting means (not shown) extend from the socket 51 to the motor 26, which may be of any type suitable for actuation by an electrical current obtained from the source of supply ordinarily provided in dwelling houses. It is, of course, to be understood that electrical conducting means are provided for connecting the electrical conducting means in the handle 48 with an electrical fixture, such as is usually installed in a house. A push button 52 is positioned in the handle 48 to control the operation of the motor while the device is being operated. Cover plates 53 and 54 are positioned, as shown, being designed to cover the ends of the tank 22 and to enhance the appearance of the device. The portion of the tank not covered by the base 25 is covered by a closure 55 which is hinged at 56. The closure 55 has a knob or handle 57 which provides a convenient means for raising the same when it is desired to refill the tank 22.

My improved mop may be operated at a slight cost and provides a practical means for thoroughly, easily and expeditiously performing the work that prior to my invention required considerable time and labor.

One of the advantages of the device lies in the fact that the moisture content of the belt 46 which contacts with the floor may be regulated, thereby preventing the marring of polished surfaces while insuring the effectual cleansing of the same.

We claim:

A mopping device comprising a frame, frame supporting rollers yieldingly carried by said frame, the ends of each supporting roller adapted to move independently of the movement of the other end of the roller, whereby said rollers are adapted to move toward or away from the frame so as to contact with the supporting surface irrespective of the contour of the surface, a mopping member arranged to travel over said rollers to contact with the supporting surface, and another supporting roller adapted to move angularly with respect to the other rollers whereby said roller is adapted to take up the slack in said mopping member and to aid in supporting said frame.
